ALONZO LINTON BAUSMAN, OF CHICOOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

CONFECTIONERY-COATING MACHINE.

1,341,253.

Specification of Letters Patent.

Patented May 25, 1920.

Application filed May 26, 1919. Serial No. 299,824.

To all whom it may concern:

Be it known that I, ALONZO LINTON BAUSMAN, a citizen of the United States of America, residing at Chicopee, in the county 5 of Hampden and State of Massachusetts, have invented certain new and useful Improvements in Confectionery-Coating Machines, of which the following is a specification.

10 This invention relates to improvements in confectionery coating machines, and particularly to machines wherein the chocolate, or other coating, is applied in a liquid state to the goods and the latter are then 15 passed from one conveying means to another while the coating is still soft.

In machines of this type, there is a tendency for the coating to be drawn out or pulled away from the goods as the latter 20 pass from one conveying means to another. This leaves a tail, so called, which is disfiguring and which it is desired to eliminate. A machine, in which means are provided for eliminating the disfiguring tails, 25 is disclosed in U. S. Letters Patent No. 1,302,205, granted April 29, 1919, on an invention of Antonio Pagliuca.

The present invention is directed to improvements in the tail removing means disclosed in such patent. As disclosed in this 30 patent, the tail removing means desirably takes the form of a roll located between the conveyer of the coating machine and the delivery conveyer. The former conveyer 35 is located within the casing of the coating machine and such casing is heated, while the latter conveyer is located outside the casing and commonly conveys the goods to a cold room. At any rate, there is a substantial difference of temperature between 40 the interior and exterior of the casing so that the coatings on the goods will be hardened. The tail removing roll described, preferably, turns in the direction of travel 45 of the conveyers and the tails removed from the goods are carried by the roll to a scraper. Due to the direction of rotation of the roll the coating material thereon is adjacent the exterior of the casing and thus subjected to 50 a lower temperature. This tends to congeal the coating on the scraper, particularly when the cold room is employed for the outer surface of the scraper is exposed to the blast of cold air issuing from such room.

The congealation of the coating on the scraper 55 leads to a piling up of frozen coating material thereon, which, if allowed to continue may eventually clog or seriously interfere with the desired operation of the machine.

According to this invention, there is interposed between the tail removing element 60 and the scraper, a member which moves in an opposite direction to said element for the purpose of conveying the coating material 65 on the element to the scraper and so conveying the material that it is exposed to the heated interior rather than to the colder exterior of the casing of the coating machine.

Other objects and advantages will appear 70 in the following description and in the illustrative embodiment of the invention, in which—

Figure 1 is a fragmentary elevational view, partly in section, of a coating machine 75 embodying the invention;

Fig. 2 is an enlarged fragmentary view showing the means for removing the disfiguring tails from the coated confections;

Fig. 3 is an enlarged fragmentary elevational view showing the driving devices for 80 said means; and

Figs. 4, 5, and 6 are diagrammatical views 85 illustrative of the operation of the tail removing means.

Referring to these drawings: A represents the casing of a confectionery coating machine, which may be of any suitable type and a full disclosure of one suitable type will be found in U. S. Letters Patent No. 735,890, granted August 11, 1903, on an invention of E. P. F. Magniez. The casing A is heated by suitable means, exemplified in part by the heating coils b. Within the casing is the usual endless conveyer c, which 95 carries the coated confections and which is usually of the wire belt type to permit excess coating to pass therethrough in a known manner.

The coated confections are carried by 100 conveyer c to one end of the heated casing A and are then transferred to a second conveyer d, by means of which they are carried into a region of lower temperature, such for example as the cold room C.

The conveyer c is driven in the usual manner and its upper lap of travel is maintained in a horizontal plane by means exem-

plified in part by the shaft *e* and member *f*. Conveyer *c* travels in the direction of the arrow, to carry the confections to belt *d*, and returns about a roll *g* to receive other confections. Excess coating material dripping from the conveyer *c* is received upon a pan *h* and flows back to the supply tank in casing *A* in the usual manner.

Conveyer *d* is supported by a cross bar *i* and a roll *j* so that its upper lap is disposed in substantially the same plane as conveyer *c*. The conveyer *d* is suitably driven from the coating machine. For example, *l* represents a driven shaft of the coating machine and such shaft drives by bevel gearing a vertical shaft *m*, which in turn drives through bevel gearing a short shaft *n*. The latter is connected by gearing *o* to drive a horizontal shaft *p*, which, by means of the worm *q* and worm gear *r*, drives roll *j*.

The adjacent ends of the conveyers *c* and *d* are arranged in close proximity to effect the transfer of the coated confections from one to the other. Located in the space between such ends of the conveyers is a roll 10, by means of which the disfiguring tails are removed from the coated confections, as fully set forth in the first-named patent. This roll is so disposed that its upper periphery lies substantially flush with the conveying surface of conveyers *c* and *d*, and preferably slightly below such surface. Roll 10 is driven, preferably in the direction of the conveyers *c* and *d*, by a chain 11 and suitable sprockets from the described shaft *e*, which is a driven shaft of the usual coating machine.

The roll 10 is rotatably supported at its ends by two spaced brackets 12 which are attached, as indicated in Fig. 2, to the casing *A*. Also journaled in brackets 12 and below roll 10 is a second roll 13, which is driven in an opposite direction from roll 10 by intermeshing gears 14 (Fig. 3). Rolls 10 and 13 contact with each other and such coating material as is removed from the confections by roll 10 is wiped therefrom by, and transferred to, roll 13. Associated with the latter is a scraper 15, the ends of which are suitably attached to lugs 16, provided on the brackets 12 described.

It is to be noted that the mechanism for removing the disfiguring tails from the confections, which mechanism includes rolls 10 and 13 and scraper 15 are all carried by the two brackets 12, which may readily be attached to the frame of any coating machine. Thus, the invention, among other things, provides an attachment which is applicable to any standard coating machine without necessitating alterations in the standard equipment.

In operation, the coated confections *s*, carried by conveyer *c*, pass therefrom, over the roll 10, to the conveyer *d*. As each

confection *s* leaves conveyer *c*, a tail *t* will be formed upon it, as shown in Fig. 4, and, on further movement of the confection, the tail *t* will break away from the end of the conveyer *c* and drop upon the upwardly turning surface of roll 10, as shown in Fig. 5. This surface is a clean surface, since any accumulations thereon have been removed by roll 13. Accordingly, the tail 10 will adhere to the bare roll 10 and, by its subsequent rotation, the tail will be swept off the end of the confection or reworked under the confection, all as more fully outlined in the first-named patent.

It is to be noted that the roll 13 conveys such accumulations of coating material, as are removed from roll 10, away from the exterior of casing *A* and toward the heated interior thereof. Moreover, the accumulations on roll 13 are lodged on that side of the scraper 15, which is exposed to the heated interior of the casing *A*, rather than to the colder exterior thereof. With roll 10 rotating in the illustrated direction, and the scraper 15 engaged directly with it, the coating material removed from roll 10 would lodge on the outer surface of the scraper and thereby be exposed to the cold air from the cold room *C*, whereby the coating material would freeze to the scraper and pile up into such an accumulation as to seriously interfere with the desired operation of the machine. With the interposed roll 13, this difficulty is eliminated and the coating material lodging on scraper 15 may flow therefrom and, even should such material not flow readily from the scraper, it will be removed by the conveyer *c* before any serious accumulation can possibly occur.

The invention has been disclosed herein, in an embodiment at present preferred, for the purposes of illustration, but the scope of the invention is defined by the appended claims rather than by the foregoing description.

What I claim is—

1. In a coating machine of the class wherein coated confections are transferred, while the coating is still workable, from a conveyer, which travels in a heated casing, to a second conveyer, which is located forwardly of the first conveyer and outside the casing, and means are disposed between the adjacent ends of the conveyers to remove the tails of the coated confections formed in leaving the first conveyer; of wiping means to clean the first named means of coating material, and means to move the wiping means to carry such material into the heated casing.

2. In a coating machine of the class wherein two conveyers, arranged one forwardly of the other with a space therebetween, are arranged to travel in regions of different temperature and means are in-

terposed in said space which present a wiping surface moving in the direction of the conveyers to remove the tails from coated confections or the like as they pass from 5 one to the other conveyer; of a means presenting a wiping surface movable in the opposite direction to clean the first-named surface of coating material and convey such material to the region of higher temperature.

10 3. An attachment for confectionery coating machines, comprising, two bearing members for attachment in spaced relation to an end of the coating machine adjacent the 15 exit of the conveying means thereof, two substantially contacting rolls mounted in said members one above the other, a scraper associated with the lower roll, and gearing

connecting the rolls to turn in opposite directions.

4. In a coating machine of the class wherein two conveyers are arranged one forwardly of the other in substantial continuation thereof with a space separating the adjacent ends of the conveyers and a 20 roll is arranged in said space with its top surface substantially flush with the running surfaces of the conveyers and driven in a general direction toward and away from the rear bottom edges of the articles borne by 25 said conveyers; of a second roll substantially contacting with the first named roll, means to drive the second roll in a direction opposite to that of the first roll, and a scraper to engage the second roll.

ALONZO LINTON BAUSMAN.
